UNITED STATES PATENT OFFICE

JAMES L. BERGGREN AND WILLIAM B. BERGGREN, OF DENVER, COLORADO

FIRE EXTINGUISHER

Application filed September 21, 1929. Serial No. 394,326.

An object of this invention is to provide an improved fire extinguisher.

A further object of the invention is to provide an improved automatic fire extinguisher.

5 A further object of the invention is to provide improved heat-operable means for the actuation of an automatic fire extinguisher.

10 A further object of the invention is to provide an improved mounting and release mechanism for containers of fire extinguishing liquids.

15 A further object of the invention is to provide an improved construction of container-fracturing means to be employed with containers of fire extinguishing liquids.

20 A further object of the invention is to provide an improved apparatus of the character described, including a fracturable container of fire extinguishing liquid and automatic, heat-operable means for fracturing said container and releasing said liquid.

25 Our invention consists in the construction, arrangement and combination of elements hereinafter set forth, pointed out in our claims and illustrated in the accompanying drawings, in which—

30 Figure 1 is a side elevation of our improved fire extinguisher as assembled and positioned for practical use. Figure 2 is a side elevation of the complete extinguisher in operating position. Figure 3 is a front elevation of the bracket and operating means employed in the improved extinguisher, the liquid container being removed and certain portions of the 35 bracket being broken away to conserve space. Figure 4 is a bottom end view of the showing of Figure 3.

35 In the construction of the improved extinguisher, as shown, the numeral 10 designates a liquid container, preferably formed of glass or similar easily fractured material in any desired shape, said container being filled with any suitable fire extinguishing liquid and suitably sealed. The pear-shaped form of 40 the container illustrated is particularly adapted for use with the other elements of our invention, but it is to be understood that any shape, form or construction of liquid container may be employed to equal advantage 45 with the other elements of the invention, so

long as it may be readily broken, and said container may be filled with any suitable liquid, the said liquid-filled container being common and well known and in itself forming no part of the instant invention. 55

In order to support the container 10, a bracket plate 11 is formed, substantially as illustrated and preferably of greater length than said container, said plate 11 being provided with a hole 12 at its upper end whereby 60 it may be conveniently supported and hung from a nail or hook and being further provided with a loop 13 secured to said plate and projecting at right angles therefrom adjacent the upper end of said plate, so that, when 65 the plate 11 is hung in vertical position the said loop 13 lies in a substantially horizontal plane in position to receive and support the container 10, said loop 13 being of a diameter slightly less than that of said container 70 so that the latter may be engaged by said loop and rest therein securely under the influence of gravity. A pair of spaced lugs 14 project perpendicularly from the surface of the plate 11 on opposite sides of the longitudinal median line of said plate and in horizontal alignment transversely thereof opposite the lower end of the container 10. A pin 15 connects the lugs 14 and pivotally supports a hammer 16 between said lugs and depending 75 vertically along the plate 11, the free end of the hammer 16 being enlarged and preferably formed as a wedge to enhance its breaking effect under impact. A wire spring 17 is formed with a central offset engaging behind 80 the shaft of the hammer 16, the free ends of the spring 17 being wound about the pin 15 on opposite sides of said hammer and bearing against the plate 11 in such manner as to normally urge the hammer 16 away from the 85 plate 11. Parallel, similar pins 18 and 19 are formed on the lower ends of the plate 11 and hammer 16, respectively, and a fusible link 20 is formed with holes adapted to receive the pins 18 and 19, so that, when the hammer 16 is pressed toward the plate 11 against the pressure of the spring 17 and the link 20 mounted on the pins 18 and 19, the normal pressure of the spring 17 holds the said link 90 on said pins as shown in Figures 1, 3 and 4. 95

In the practical operation of the improved fire extinguisher, the elements being assembled and arranged as shown in Figure 1, any fire breaking out in the immediate vicinity of 5 the extinguisher unit will fuse and destroy the link 20, thus releasing the hammer 16 and permitting said hammer to be swung upwardly through a vertical arc to a sharp impact between the wedge end of said hammer 10 and a point on the container 10, breaking said container and releasing the liquid therein to attack and smother the fire. When any extinguisher unit has been used and discharged its liquid, it may readily be recharged by 15 simply inserting a new container in the loop 13 and mounting a new link on the pins 18 and 19. Any number of complete extinguisher units may be employed to give the degree of protection desired and the units may conveniently be moved about from one location to 20 another as the fire hazard varies.

Since modifications and changes in the form and arrangement of the elements of the invention may be had without departing 25 from the spirit of the invention, we wish to be understood as being limited solely by the scope of the appended claims rather than by the specific illustrative showing and foregoing description.

30 We claim as our invention—

1. An automatic fire extinguisher comprising a flat plate, a loop fixed adjacent one end of said plate and defining a plane transversely of and perpendicular to the plane of 35 said plate, a frangible, liquid-filled container seated in and supported by said loop, a striker hinged to said plate in position to be swung against said container, spring means engaging said plate and striker whereby the latter is normally urged against said container, similar pins in corresponding relation on said plate and striker and a fusible link formed with spaced holes loosely engaging said pins whereby said striker may be 40 positioned and held adjacent said plate and out of contact with said container against the pressure of said spring means.

2. An automatic fire extinguisher comprising a flat plate, a hole adjacent one end of 50 said plate whereby the latter may be supported in vertical hanging position, a loop fixed to said plate adjacent said hole and defining a plane transversely of and perpendicular to the plane of said plate, a frangible, liquid-filled container seated in and supported by said loop in spaced relation with 55 said plate, a striker hinged to said plate in position to be swung against and break said container, spring means engaging said plate and striker whereby the latter is normally urged against said container, pins projecting longitudinally from said plate and striker in spaced, parallel relation when said striker 60 is positioned against said plate and a fusible link engaging said pins to hold said striker 65

adjacent said plate against the pressure of said spring means.

3. In an automatic fire extinguisher, a supporting plate, a loop extending perpendicularly from and transversely of said plate, a 70 frangible, liquid-filled container seated in and supported by said loop, a striker hinged to said plate in position to be swung against said container, spring means engaging said plate and striker whereby the latter is normally urged against said container and means including a fusible link engaging pins on said plate and striker whereby the latter may be positioned and held adjacent said plate against the pressure of said spring means. 80

4. In an automatic fire extinguisher having a frangible, liquid-filled container adapted to be broken for the release of its liquid contents, container, supporting and breaking means comprising a plate adapted to be hung on a suitable support in vertical position, a container seat on said plate in the form of a loop extending perpendicularly from and transversely of said plate, spaced lugs on and perpendicular to said plate, a pin connecting said lugs, an arm hinged at one end to said pin and depending therefrom, a striker on the free end of said arm, a spring wound about said pin on each side of said arm and formed with a loop engaging behind said arm and free ends engaging said plate, whereby said arm is normally urged through an upward arc to bring its striker into breaking engagement with said container, pins projecting longitudinally from the free end of said arm and the lower end of said plate and a fusible link formed with spaced holes to receive said pins and hold said arm adjacent said plate against the pressure of said spring. 90

5. In an automatic fire extinguisher having a bracket plate formed with a transverse, perpendicular loop and a frangible, liquid-filled container seated in said loop, heat-operable means for the automatic breaking of said container to release its liquid contents, said means comprising spaced lugs on and perpendicular to said plate, a pin connecting said lugs, an arm hinged at one end to and depending from said pin, a striker on the free end of said arm, spring means engaging said plate, pin and arm whereby the latter is normally urged through a vertical arc to bring its striker into breaking engagement with said container, pins projecting longitudinally from the free end of said striker arm and the lower end of said plate and a fusible link formed with spaced holes to receive said pins and hold said arm adjacent said plate against the pressure of said spring means. 100

Signed at Denver, in the county of Denver and State of Colorado, this twenty-third day of August, 1929.

JAMES L. BERGGREN.
